[57] CLAIM

The ornamental design for a container lid, as shown and described.

DESCRIPTION

FIG. 1 is a perspective view in open position of a container lid showing our new design;

FIG. 2 is a top plan view in an open position;

FIG. 3 is a bottom plan view in an open position;

FIG. 4 is a side elevational view in open position and partly in section;

FIG. 5 is a front elevational view in a closed position and partly in sections; and

FIG. 6 is a side elevational view of the lid in a closed position and partly in section.

The broken lines in FIG. 1 showing a container are for the purpose of illustrating environmental use only.
